UNITED STATES PATENT OFFICE.

LEO DAVID HAAS AND EDWIN GEORGE DERBIDGE, OF SAN JOSE, CALIFORNIA.

DISTURBANCE-OPERATED CIRCUIT-BREAKER.

No. 893,997.

Specification of Letters Patent.

Patented July 21, 1908.

Application filed November 3, 1906. Serial No. 341,852.

To all whom it may concern:

Be it known that we, LEO D. HAAS and EDWIN G. DERBIDGE, citizens of the United States, and residents of San Jose, in the 5 county of Santa Clara and State of California, have invented a new and Improved Disturbance-Operated Circuit-Breaker, of which the following is a full, clear, and exact description.

10 Our invention relates to circuit breakers, our more particular object being to produce a type of circuit breaker in which action while not automatic is brought about by some unusual disturbance, such for instance as an 15 earthquake, a cyclone or violent shock of an exceptional character.

Reference is to be had to the accompanying drawing forming a part of this specification, in which the figure is a vertical section 20 through our improved apparatus.

A casing 1 is provided with a base 2 and may be placed underground or in some inaccessible spot. Mounted upon the base 2 is a standard 3 having a bracket 4 adjustably 25 mounted thereupon and provided with a part 5 serving as a binding post. The bracket 4 is further provided with an aperture 6 of circular form, the inner edge of which is rounded. A bracket 7 is connected with the upper end 30 of the standard 3 by means of a screw 8, which also serves as a binding post.

The bracket 7 is provided with a bowl-like aperture 9 and with a conical aperture 10 merging therewith. A rod 11 of metal or 35 other conducting material is provided at its upper end with a ball 12 and at its lower end with a thread 13. A weight 14 is mounted upon the thread 13, and by being turned may be adjusted vertically upon the rod 11. 40 This rod normally occupies the center of the aperture 6.

From the binding post 8 a wire 15 leads to a solenoid 16 and thence a wire 17 leads to a battery 18 or equivalent source of electricity; 45 from the latter a wire 19 leads to the binding post 5. The solenoid 16 is provided with an armature 20.

A base 21 is provided with a switch arm 22 journaled thereupon and connected with the 50 armature 20 by means of a link 23. A contact button 24 and a blind or dead button 24^a are mounted upon the board 21. The switch arm 22 and the contact button 24 are connected respectively with leads 25 and 26,

which pass into the casing 1 through apertures 27 and 28.

The leads 25, 26, may represent the mains of an electric lighting system or those used for supplying current for the propulsion of machinery.

It will be understood that while we show a battery 18 we do not limit ourselves thereto, for the reason that any other known source of electricity may be employed as an equivalent.

The action of our device is as follows: The rod 11 being centered as above described, presents comparatively little friction owing to the fact that the under surface of the ball 12 makes but little contact, resting in the bottom of the bowl-like aperture 9, and the rod 11 may therefore be swung like a pendulum. The sensitiveness of the rod 11 may be controlled to some extent by adjusting the height of the ball 14, which is 65 done by merely turning the latter. The parts being connected as indicated, we will suppose that an earthquake takes place or that a cyclone comes along, or that some similar exceptional disturbance occurs. The 70 ball 14 because of its inertia tends to remain stationary, whereas the seismic disturbance moves the base, standard 3, and the brackets 4, 7; such being the case, the rod 11 being displaced relatively to the aperture 6, makes contact with the bracket 4, 75 thereby completing the following circuit: Source of electricity 18, wire 17, solenoid 16, wire 15, binding post 8, bracket 7, rod 11, bracket 4, binding post 5, wire 19, back to 80 source of electricity 18. This energizes the solenoid 16, causing the same to draw the armature 20, and this movement disconnects the switch arm 22 from the contact button 24, thereby opening the circuit through the 85 leads 25, 26, and switch arm 22.

Our invention is of especial service for shutting off electric power in cities where disturbances of the kind above described are liable to take place. It will be understood 90 that owing to the flow of heavy currents through the mains in a city, great damage may be done in case the insulation of the main wire is wholly or partly disturbed, and it is desirable in order to avoid the possibility of fire, to shut off the power the instant the earthquake or cyclone or unusual vibrations take place.

We do not limit the use of the apparatus to opening electrical circuits, for the reason that it may obviously be used for shutting off power of any kind, controllable by a movable member such as the switch arm 22.

Having thus described our invention we claim as new and desire to secure by Letters Patent:

The combination of a standard of insulating material, a bracket of conducting material provided with an aperture, said bracket being adjustable relatively to said standard in the general direction of the length thereof, a second bracket of conducting material mounted upon said standard, a pendulum rod suspended from said last-

mentioned bracket and extending through said aperture of said first-mentioned bracket, a weight mounted upon said pendulum rod and adjustable relatively thereto for the purpose of varying the sensitiveness of said pendulum rod to disturbing influences, and electrical connections for said brackets.

In testimony whereof we have signed our names to this specification in the presence of 25 two subscribing witnesses.

LEO DAVID HAAS.
EDWIN GEORGE DERBIDGE.
